(57) **CLAIM**

The ornamental design for a basketball goal cover, as shown and described.

DESCRIPTION

FIG. 1 is a left side elevational view of the basketball goal cover showing the new design, the right side being a mirror image thereof;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a top, right, front perspective view thereof, the bottom flap in a partially open position.
